BRIDGE LAMP

Filed May 27, 1929

Max Boltuch
INVENTOR.

BY Louis Barnett
ATTORNEY

UNITED STATES PATENT OFFICE.

MAX BOLTUCH, OF NEW YORK, N. Y.

DESIGN FOR A BRIDGE LAMP.

Application filed May 27, 1929. Serial No. 31,417. Term of patent 3½ years.

To all whom it may concern:

Be it known that MAX BOLTUCH, citizen of Poland, and resident of New York city, in the county of Kings and State of New York, has invented a new, original, and ornamental Design for a Bridge Lamp, of which the following is a specification, reference being had to the accompanying drawing, forming part thereof, in which the figure is a perspective view of a bridge lamp embodying the invention.

I claim:

The ornamental design for a bridge lamp, as shown.

Dated New York city, May 15, 1929.

MAX BOLTUCH.
